No. 650,833.

Patented June 5, 1900.

F. T. GRACEY.

DEVICE FOR MAKING CIGARETTES.

(No Model.)

(Application filed Sept. 22, 1899.)

UNITED STATES PATENT OFFICE.

FRANK T. GRACEY, OF ADAIRVILLE, KENTUCKY, ASSIGNOR OF ONE-HALF
TO FRANK G. WAKE, OF SAME PLACE.

DEVICE FOR MAKING CIGARETTES.

SPECIFICATION forming part of Letters Patent No. 650,833, dated June 5, 1900.

Application filed September 22, 1899. Serial No. 731,300. (No model.)

To all whom it may concern:

Be it known that I, FRANK T. GRACEY, a citizen of the United States, residing at Adairville, in the county of Logan and State of Kentucky, have invented certain new and useful Improvements in Devices for Making Cigarettes, of which the following is a full, clear, and exact specification.

My present invention relates to improvements on the device for which Letters Patent No. 593,822 were granted to me and J. H. Tabler November 16, 1897; and it consists in certain novel features hereinafter described and claimed.

In the accompanying drawings, which fully illustrate my invention, Figure 1 is a view of a tobacco-bag with my cigarette-making device attached thereto, the tube or filler being turned down against the bag in position to be carried in the user's pocket. Fig. 2 is a view partly in elevation and partly in section, showing the device in the position assumed during the making of a cigarette. Fig. 3 is a sectional view of the tube or filler, a modified construction of the tube being shown. Fig. 4 is a detail sectional view of a modified form of the device; and Fig. 5 is a similar view showing another modification, in which the tube is attached permanently to the bag or pouch.

My present improvements aim to overcome clogging of the tobacco in the tube, prevent loss of tobacco through the end of the bag around the tube, and permit turning of the tube freely in forming the cigarette-wrapper.

The bag or pouch A may be of the usual size and construction. In the drawings the bag is illustrated as having a draw-string in its upper end adapted to be tightened around the tube or around the sleeve.

The tube or filler B may be formed in a single piece or section, or it may be made in two sections swiveled together, as shown at C. It is desirable to have the outer portion of the tube turn with the paper when forming the cigarette-wrapper, and this turning is permitted by the swiveled construction. The swivel, furthermore, forms a bead which acts as a guide or gage for the end of the wrapper; but it will be readily understood that the continuous tube may be provided

with a bead to serve as a guide or gage, although I have deemed it unnecessary to illustrate such construction. Secured to the inner end of the tube is a cap D, preferably of rubber, which has its outer end or edge secured to a collar or sleeve E, surrounding the tube. The collar or sleeve is provided with an annular groove F, and the mouth of the bag or pouch may be secured in this groove or it may be drawn tightly around the tube beyond the collar. It will be seen at once that this cap forms a guard or closure to prevent crumbs of tobacco passing between the bag and the tube or the collar and the tube, and it thereby prevents loss of tobacco and also keeps the outer side of the tube clean and free to turn. Clogging of the tobacco within the tube is prevented by a non-rotatable stirrer G, which is preferably in the form of a saw having a slight twist. This stirrer extends longitudinally through the tube and is supported by a yoke H, having its sides extending down to the collar or sleeve E and secured thereto in any convenient manner. It has been found in practice that the tobacco is fed more readily through the tube when a twisting motion is imparted to the tube, and this twisting motion of the tube carries the tobacco against the stirrer and causes the stirrer to keep the particles of tobacco separated, and thereby prevents clogging in the tube. Pieces of stems which have commingled with the tobacco will be fed endwise through the tube and into the wrapper, and consequently will not puncture the wrapper. When the tube is not in use, it will be turned down against the bag and held by a pocket or other retaining device I at the lower end of the bag, the bag then forming a closure for the tube, as will be readily understood on reference to Fig. 1.

In Fig. 4 I have shown a modification of the device in which the inner end of the tube is formed into a funnel J, having a lateral flange K, which fits so as to rotate freely in an internal groove in a band or collar L, having a neck M, to and around which the mouth or end of the bag is closely secured. The stirrer is secured to and carried by this band or collar.

In Fig. 5 I have shown a modification in-

tended more especially for a cheap grade of goods. In this construction the inner end of the tube is provided with a number of radial teeth N, permanently attached to the mouth 5 of the bag, and the stirrer is secured to these teeth or the end of the tube.

In making cigarettes by means of this device the wrapper is formed around the tube and the end or edge of the wrapper is crimped 10 and held by the thumb of the operator. The tube and the bag are then turned into a vertical position, so that the tobacco will run into the tube and be supported by the crimped closed end of the wrapper. The bag is compressed by the left hand, so as to force the requisite quantity of tobacco into the tube. The bag is then turned to one side of the tube, so as to cut off the flow, and the wrapper gradually drawn from the tube, the end 15 of the tube being manipulated to pack the tobacco in the wrapper. After the cigarette thus formed is drawn from the tube the finger is placed over the open end of the tube and the tube is slightly shaken in order to 20 return to the bag any crumbs of tobacco which may have been left in the tube.

This device is very light and cheap and enables the smoker to make his own cigarettes rapidly and without any loss of tobacco. The 25 cap between the end of the tube and the collar thereon prevents loss of tobacco through the mouth of the bag, and if the cap be made of rubber, it will aid in preventing clogging in the tube, inasmuch as the bag is always twisted in the operation of making the cigarette and a tension thereby put on the cap which will react to turn the tube when the hold on the bag is released.

Having thus described my invention, what

I claim, and desire to secure by Letters Patent, is—

1. A pocket cigarette-maker consisting essentially of a pouch or bag, a rotatable tube attached to the mouth of the same, and a non-rotatable stirrer supported at the inner 45 end of the tube and extending longitudinally through the tube.

2. A device for making cigarettes adapted to be attached to the mouth of a tobacco-bag, consisting essentially of a rotatable tube, a 50 collar mounted loosely on the inner end of the said tube, and a cap or guard secured to and surrounding the said collar and the end of the tube.

3. In a device for making cigarettes, the combination of a rotatable tube or filler, a collar mounted thereon and adapted to have a tobacco-bag secured thereto, a yoke secured to the said collar, and a non-rotatable stirrer carried by the said yoke and extending longitudinally through the tube or filler. 55

4. A device for making cigarettes adapted to be attached to the mouth of a tobacco-bag, consisting essentially of a rotatable tube or filler, a collar mounted loosely thereon, a cap 60 or guard secured to the said collar and the end of the tube, a yoke secured to the collar, and a non-rotatable stirrer carried by the said yoke and extending longitudinally through the tube. 65

In testimony whereof I have signed this specification in the presence of two subscribing witnesses.

FRANK T. GRACEY.
